UNITED STATES PATENT OFFICE.

WILLIAM ASBURY, OF NEW YORK, N. Y., ASSIGNOR TO SQUARE DEAL MACHINE CO., OF NEW YORK, N. Y.

VENDING-MACHINE.

No. 921,388.

Specification of Letters Patent.

Patented May 11, 1908.

Application filed May 9, 1908. Serial No. 431,779.

To all whom it may concern:

Be it known that I, WILLIAM ASBURY, a subject of the King of Great Britain, and a resident of the city of New York, borough of 5 Manhattan, in the county and State of New York, have invented a new and Improved Vending-Machine, of which the following is a full, clear, and exact description.

One object of my invention is to provide a 10 vending machine for selling postal cards and other such merchandise.

Another object of my invention is to provide a vending machine for selling postal cards and postage stamps at a profit, by 15 means of advertising on or in the envelopes containing the postage stamps or postal cards.

Another object is to provide a vending machine with an effective mechanism by the 20 means of which a practical two coin machine is produced.

Other objects of the invention are to provide means for rotating the commodity receptacle as well as means for freeing the bottom card, or other merchandise, when the commodity receptacle reaches a predetermined position.

Still other objects of the invention are referred to in the following more complete 30 description of the invention:

In this specification I will describe my preferred form of the machine but I do not limit myself thereto as I consider myself entitled to all forms and embodiments of the 35 invention which may be held to fall within the scope of the appended claims.

Reference is to be had to the accompanying drawings, forming a part of this specification, in which similar characters of reference indicate corresponding parts in all the 40 figures, in which—

Figure 1 is an elevation of the invention; Fig. 2 is a sectional elevation of the invention showing the principal working members 45 of the machine; Fig. 3 is a sectional plan view showing the commodity receptacle and the means by which it is supported in a position for rotation; Fig. 4 is an enlarged sectional plan view taken on a line just below one of the commodity receptacles; Fig. 5 is an enlarged sectional view showing the inner or lower terminal of the two penny coin chutes with the trip mechanism operated

and the lever attached to the rock shaft throwing the slide to operate the ejecting 55 mechanism; Fig. 6 is a similar view showing the penny mechanism which is in position to be actuated by a penny introduced in the slot; Fig. 7 is an enlarged view showing the rollers for supporting the commodity in the 60 commodity receptacle; Fig. 8 is an enlarged view showing the roller supports for the commodity receptacle; Fig. 9 shows a modified means by which a backward movement of the commodity receptacle is prevented; and 65 Fig. 10 is an enlarged sectional view showing the inner or lower terminal of the five cent coin chute of the trip mechanism in position to be operated by a coin.

By referring to the drawings it will be 70 seen that the machine is provided with a casing 1, which I prefer to make with the corner posts 2, of metal, to which are secured glass plates on the four sides, permitting the mechanism of the machine to be seen by 75 purchasers. The drawings show a machine in which four commodity receptacles are supported with a respective operating mechanism and coin chutes. In this specification I will describe only one of the commodity receptacles with its operating mechanism and coin chute, it being understood that the other commodity receptacles and their mechanisms are constructed in the same manner.

Each of the coin chutes 85 extends horizontally over a short distance, then vertically and then obliquely until it is nearly to the operating mechanism. Each of the coin chutes 3 has a companion 4, the companion chute 4 being provided to direct 90 slugs and other foreign matters away from the operating mechanism. As is seen in Fig. 2 the coin chute 3 with its companion 4 unite near their upper terminals and over the companion chute 4 is disposed a magnet 95

5. By this arrangement, when a slug is introduced in the coin chute entrance 6, it will be attracted by the magnet and also because of its weight it will be directed to the companion chute 4, so that there will be no 100 danger of it reaching the operating mechanism and the slug will fall directly into the money drawer 7. When the machine is to be used as a one coin machine the coin will fall direct to the trip 8 of the trip lever 9. 105 and when the device is used as a two coin

machine it will first come in contact with the coin director 10 which is pivoted in the coin chute 3 at a place where the coin chute is doubled in width to provide two coin passages 11 and 12 with a partition 13 therebetween. The coin director 10 has a long arm 14 which is adapted to come in contact with the diverging walls of the coin chute 3 and the coin director 10 also has tappets 15 which are adapted to come in contact with the partition 13 when the coin director 10 swings on its pivot. By this construction it will be seen that when the coin director is in its proper position as shown in Fig. 2, the first coin introduced in the coin chute will fall into the passage 12, throwing the coin director 10 to the position shown by the dotted lines, so that when the next coin is introduced in the coin chute it will fall on the trip 8 of the trip lever 9, throwing the trip lever 9 in position to be operated by the arm 16 which is secured to the rock shaft 17. When the machine is used as a one coin machine this coin director 10 is omitted, and in cases where the merchandise is to be sold for one cent, the inner and lower terminal of the coin chute is constructed as shown in Fig. 6, in which the coin passage 11, which is a continuation of the coin chute 3, leads direct to the trip 8^a of the trip lever 9 while the passage 12 is a direct continuation of the companion coin chute 4, which is provided to direct slugs, &c., direct to the back without their coming in contact with the trip 8^a of the trip lever 9. When the machine is to be used as a five cent piece machine, the lower terminal of the coin chute is constructed as is shown in Fig. 10 in which the coin chute 3 and its companion chute 4 are disposed in the same way as with the one cent machine except that there is an opening between the coin chute 3 and its companion chute 4, which opening is in direct alignment with the obliquely disposed portion of the coin chute 3, so that the pennies and other coins, other than five cent pieces, will pass through the said coin chute 3, through the said opening which I will designate 18, into the companion chute 4 so that only five cent pieces will fall on the trip 8 to operate the trip lever 9. It will be seen that in the one cent machine the trip 8^a has a larger body than the trip 8 in the five cent machine, but it will be understood that the size of the trip may be regulated to be actuated by coins of different size and widths to obtain the best results.

To the frame 19 of the machine, to which the lower terminals of the coin chutes are secured, are fastened slide guides 20 which are adapted to support the slide 21 and permit it to slide at right angles to the lower terminals of the coin chutes. To this slide 21 is pivoted the trip lever 9 having the trip 8 which is adapted to have more or less of its body

disposed under the coin chute 3 when the mechanism is in operative position. The other arm 22 of this trip lever 9 is constructed so that it is adapted to engage the slot 23 at the lower end of one of the slide guides 20. The trip lever 9 not only has a trip 8 or 8^a which is disposed so that it will be adapted to engage a coin introduced into the slot, but it also has an offset 24 which is adapted to be so disposed that when the trip 8 is operated by a coin, it will be in the path of the arm 16 which is secured to the rock shaft 17. This rock shaft is journaled in a plate 25 which is secured to the frame of the machine, and to this plate 25 is also fastened a spring holder 26 to which a wire spring 27 is secured, this wire spring 27 being adapted to bear slightly on the offset 24, to make certain that the trip 8 will be properly disposed to be actuated by the coin introduced in the coin chute. There is also pivoted to the slide 21, an arm 28, which is adapted to move in an opening 29 in one of the slide guides 20, the said arm 28 having an offset 30 which is adapted to engage with the arm 16 secured to the rock shaft 17, and the arm 28 also has a shoulder 31 which is adapted to engage with the opening 29 in the slide guides 20. Secured to the slide 21 is a spring 32, which is adapted to hold the slide so that the trip will be disposed under the coin chute, the wire spring 27 being adapted to engage the offset 24, so that the trip 8 will be held at the proper angle relatively to the coin chute. A spring 33 is also provided, this spring being adapted to hold the arm 16 away from the offset 24. As it will be hereinafter described the end 34 of the slide 21 is secured to the mechanism by which the commodity receptacle is rotated to eject the postal cards or other commodity.

Referring now to one of the commodity receptacles, the others being constructed in the same manner, it will be seen that the frame 19 is in effect the bed plate of the machine which supports the commodity receptacles, the trip mechanism being disposed therebelow. Each of the commodity receptacles is composed of a plate 35 which has a cruciform opening 36 therein. To the outer corners 37 of this cruciform opening 36 in the plate 35 are secured angle irons 38 which are disposed vertically, the said angle irons being connected in pairs at their outer terminals by frame members 39. The plate 35 of the commodity receptacle is supported by rollers 40 which are disposed above and beneath it so that it will be held firmly in place. These rollers are journaled in roller supporters 41 which are secured to the frame of the body plate 19 of the machine. In the drawings I show four sets of these rollers for each of the commodity receptacles, but it is understood that any number of pairs of the rollers may be used and that they may be

disposed at the top as well as at the bottom of the commodity receptacle. There is an oblong opening 42 in the body plate 19 of the machine; and the commodity receptacle is so disposed thereover that when it reaches a predetermined position in its rotation it will present an opening in alinement with the opening 42 and of approximately the same size, so that any commodity contained in the commodity receptacle, which is in alinement with the opening, will pass through the opening 36 in the plate 35 of the commodity receptacle and also in the opening 42 in the frame 19, and will then fall on the commodity chute 43, down which it will slide in an opening in the machine until it is stopped by the check 44, from which it may be taken by the purchaser. The commodity which is not in alinement with the said openings in the plate 35 of the commodity receptacle and in the frame 19 respectively, is supported by commodity supporting rollers 45, which are disposed at right angles to the ends of the openings 42 in the frame plate 19 and are supported on the said frame plate. I propose to so mount the rollers 45 in pairs that they will offer the least resistance to the commodity which they support, when the commodity receptacle is being rotated. The rollers 45 are mounted in a frame 46 which is secured to the frame plate 19. Underneath the plate 35 of the commodity receptacle are fastened studs 47, the studs being four in number and being disposed at equal distances apart and also an equal distance from the center of the said plate. To the frame of the machine is secured a spring 48 with which the studs 47 are adapted to engage when the commodity receptacle is rotated, this spring 48 being adapted to prevent any return movement of the commodity receptacle. In Fig. 9 at 48^a is shown a ratchet, which I may use in place of the spring 48 to engage with the studs 47 and prevent the return movement of the commodity receptacle.

On the frame 19 of the machine is journaled a short shaft 49 having an arm 50 secured thereto, the arm 50 being disposed below the frame plate 19 and being adapted to engage the slide 21 at its end 34, and as shown in the drawings this engagement is secured by having the arm 50 extend through an opening 51 in the slide 21. The other arm 52 which is secured to the short shaft 49 above the frame plate 19 has, near its outer terminal a slot 53, which is disposed at a slight angle to the main body of the arm 52 with an offset 54 at one side of the said slot 53 and a curved surface 55 on the other side, the arm 52 also being provided with a tapering surface 56 and a lateral opening 57 with a shoulder 58. The slot 53 of the arm 52 is adapted to engage the studs 47, and when the mechanism which operates the arm 52 is actuated, the arm 52 in connection with the

studs 47 is adapted to rotate the commodity receptacle, giving it a one-quarter revolution at every movement of the operative mechanism.

As shown in the drawings a plurality of commodity receptacles, with their respective operating mechanism and coin chutes, may be disposed in the frame 1 of the machine, and I propose to mount the machine on a pedestal 60 so that it may rotate, permitting the purchaser to bring before him the commodity receptacle containing the goods which he desires to purchase, with its respective operating mechanism and coin chute. The money drawer 7 is bifurcated, permitting it to slide on either side of the pedestal 60, which is supported on a base plate 61.

The vending machine is operated as follows: A coin is introduced into the coin slot 6 and it falls down the coin chute 3, but if a slug is introduced in the coin slot 6 it will fall down the companion chute 4 away from the operating mechanism, into the coin drawer 7. Should, however, a coin be introduced which is not attracted by the magnet 5 in the coin chute 4, it will fall down the coin chute 3 along its obliquely disposed portion, but it may still reach the companion chute 4 through the opening 18 in the companion chute 4 if the coin is not of proper weight to cause its falling in the vertically disposed inner terminal of the coin chute 3. If the coin continues in the coin chute 3 it may reach the trip 8 or 8^a direct, or if the machine is a two coin machine it will reach the coin director 10; the first coin falling in the coin passage 12 and operating the coin director 10 so that it will assume the position shown in the dotted lines in Fig. 2 of the drawings and a second coin will then fall on the trip 8 or 8^a. When the coin falls on the trip 8 its weight causes the trip to bear down so that the offset 24 is in position to be engaged by the arm 16 secured to the rock shaft 17 and when the rock shaft 17 is operated by its respective handle 59 it will engage the offset 24 and will push the trip lever 19, together with the slide 21, to the left, the arm 22 of the trip lever 9 being so disposed as to engage the slot 23 and the arm 28 which is pivoted to the slide 21 will be drawn through the opening 29 in the slide guide 20 until the shoulder 31 engages the lower portion of the said opening 29. During this movement of the slide 21 the arm 50 has been operated by means of the slide 21 and has caused a rocking movement of the shaft 49 by means of which the arm 52 has been moved to the right and as one of the studs 47 has been disposed in the slot 53 of the said arm 52, the plate 35 of the commodity receptacle to which the studs 47 are secured has been caused to rotate the stud 47 which engages the arm 52 during its rotation, moving along the slot 53 and up on the tapered portion 56 until it slips off into the lat-

eral opening 57 at one-quarter of a revolution of the commodity receptacle. The shaft 49 is so disposed that in the one-quarter revolution of the commodity receptacle, 5 the radius between the shaft 49 and the stud 47 which is engaging the slot 53 is decreased so that it will travel in the said slot 53 up the tapered surface 56 and into the lateral opening 57 as has been described. When the 10 commodity receptacle has made a one-quarter revolution the arm 52 is parallel with the sides of the opening 42 of the frame plate 19, and no longer extends across the said opening, and as there is an oblong opening in the 15 bottom of the commodity receptacle which is in alinement with the opening 42 in the frame plate 19, any commodity in alinement with the said two openings may fall through the plate 35 of the commodity receptacle and 20 also through the frame plate 19 of the machine into the commodity chute 43 and down to the commodity stop 44.

It is my purpose to pack the postal cards or other commodity packages alternately at 25 right-angles to each other in the commodity receptacles so that at every one-quarter revolution a single postal card or commodity package will be brought in alinement with the opening 42 in the frame plate 19 and away 30 from the commodity supporting rollers 45 so that it will be free to fall through the plate 35 of the commodity receptacle and the frame plate 19, as has been described, but of course, it will be understood that a plurality of 35 packages may be placed in the machine next to each other in alinement so that any desired number of postal cards or commodity packages may be ejected from the machine by one operation of the mechanism. At each 40 one-quarter revolution of the commodity receptacle the ratchet 48 engages a new stud 47 so that any return movement of the commodity receptacle is prevented.

Having thus described my invention, I 45 claim as new and desire to secure by Letters Patent:

1. In a vending machine, a commodity receptacle adapted for rotating consisting of a plate with an enlarged opening in its center 50 of rotation and vertical members which are adapted for preventing the lateral displacement of the commodity packages, roller supporters disposed around the plate, and rollers which are journaled in the roller supporters, 55 the said rollers engaging the plate near its periphery on its upper and lower faces respectively for supporting the commodity receptacle.

2. In a vending machine, a commodity 60 receptacle adapted for rotating, a pivoted arm for rotating the commodity receptacle, the center of rotation of the commodity receptacle being at a distance laterally from the pivot on which the arm is mounted, the 65 arm being disposed substantially at right-

angles to the axis of the commodity receptacle with its terminal adapted for describing an arc beyond the axis of the commodity receptacle, means on the arm which are adapted for co-acting with means on the 70 commodity receptacle to enable the arm to rotate the commodity receptacle, and means on the commodity receptacle which are adapted to be engaged by the arm to enable the arm to rotate it. 75

3. In a vending machine, a commodity receptacle consisting of a plate with an opening therein, vertical members which are adapted for preventing the lateral displacement of the commodity packages, 80 rollers which engage the plate for supporting the commodity receptacle and permit it to rotate, an arm for rotating the commodity receptacle, and means for automatically locking the arm to the commodity receptacle as it is moved relatively thereto. 85

4. In a vending machine, a commodity receptacle which is adapted to move relatively to the frame of the machine, a stud on the commodity receptacle, and a spring arm having a slot and a lateral recess therein, there being a tapered surface on the arm which extends from one side at one end of the slot to the opposite side of the arm near the lateral recess, the slot in the arm being adapted 90 to engage the stud to operate the commodity receptacle when the arm is actuated, the stud being adapted to ride up the tapered surface of the arm to the lateral recess. 95

5. In a vending machine, a commodity 100 receptacle which is adapted to rotate relatively to the frame of the machine, a stud on the commodity receptacle, and a spring arm having a slot and a recess therein, there being a tapered surface on the arm which extends 105 from one side at one of the ends of the slot to the opposite side of the arm near the lateral recess, the slot in the arm being adapted to engage the stud to operate the commodity receptacle when the arm is actuated, the 110 stud being adapted to ride up the tapered surface to the lateral recess.

6. In a vending machine, a commodity receptacle which is adapted to be rotated relatively to the frame of the machine, a stud on the commodity receptacle, and a pivoted arm having a slot and a lateral recess therein, there being a tapered surface on the arm which extends from one side at one of the ends of the slot to the opposite side of the 120 arm near the lateral recess, there being a lateral tapered surface on the side of the arm which is opposite the side in which there is the recess, the center of rotation of the commodity receptacle being at a distance laterally from the pivot on which the arm is mounted, the lateral tapered surface permitting the stud to ride up on the arm to the slot, in which it is adapted to travel and to ride up its tapered surface to the lateral 125 recess. 130

cess as the arm is actuated thereby rotating the commodity receptacle.

7. In a vending machine, a commodity receptacle consisting of a plate with an opening therein and vertical members which are adapted to prevent the lateral displacement of the commodity packages, rollers which engage the plate near its periphery to support the commodity receptacle and permit it to rotate, a stud on the commodity receptacle, and an arm having a slot and a recess therein, there being a tapered surface on the arm which extends from one side at one of the ends of the slot to the opposite side of the arm near the lateral recess, the slot in the arm being adapted to engage the stud for operating the commodity receptacle when the arm is actuated, the stud being adapted to ride up the tapered surface to the lateral recess.

8. In a vending machine, a commodity receptacle consisting of a plate with an opening therein and vertical members which are adapted to prevent the lateral displacement of the commodity packages, rollers which engage the plate to support the commodity receptacle and permit it to rotate, a stud on the commodity receptacle, and a pivoted arm having a slot and a lateral recess therein, there being a tapered surface on the arm which extends from one side at one of the ends of the slot to the opposite side of the arm near the lateral recess, there being a lateral tapered surface on the side of the arm which is opposite the side in which there is the recess, the center of rotation of the commodity receptacle being at a distance laterally from the pivot on which the arm is mounted, the lateral tapered surface permitting the stud to ride up on the arm to the slot in which it is adapted to travel and to ride up its tapered surface to the lateral recess as the arm is actuated thereby rotating the commodity receptacle.

9. In a vending machine, a commodity receptacle consisting of a plate with an opening therein and vertical members which are adapted to support adjoining commodity packages out of alignment with each other, rollers adapted to support the lowermost commodity package, a second set of rollers which engage the plate to support the commodity receptacle and permit it to rotate, a stud on the commodity receptacle, and a pivoted arm having a slot and a lateral recess therein, there being a tapered surface on the arm which extends from one side at one of the ends of the slot to the opposite side of the arm near the lateral recess, there being a lateral tapered surface on the side of the arm which is opposite the side in which there is the recess, the center of rotation of the commodity receptacle being at a distance laterally from the pivot on which the arm is

mounted, the lateral tapered surface permitting the stud to ride up on the arm to the slot in which it is adapted to travel and to ride up its tapered surface to the lateral recess as the arm is actuated thereby rotating the commodity receptacle.

10. In a vending machine, a commodity receptacle base having an enlarged opening in its center, roller supporters disposed therearound, and rollers journaled in the roller supporters, the said rollers being disposed above and below the base respectively for supporting the commodity receptacle base and permitting it to rotate.

11. In a vending machine, a commodity receptacle consisting of a base having an enlarged opening in its center and vertical members which are adapted for preventing the lateral displacement of commodity packages, roller supporters disposed around the base, and rollers journaled in the roller supporters, the said rollers being disposed above and below the base respectively for supporting the base and permitting it to rotate.

12. In a vending machine, a commodity receptacle adapted for rotating consisting of a plate with an enlarged opening in its center of rotation and vertical members which are adapted for preventing the lateral displacement of the commodity packages, roller supporters disposed around the plate, rollers which are journaled in the roller supporters, the said rollers engaging the plate near its periphery on its upper and lower faces respectively for supporting the commodity receptacle, a pivoted arm for rotating the commodity receptacle, the center of rotation of the commodity receptacle being at a distance laterally from the pivot on which the arm is mounted, the arm being disposed substantially at right-angles to the axis of the commodity receptacle with a terminal adapted for describing an arc beyond the axis of the commodity receptacle, means on the arm which are adapted for co-acting with means on the commodity receptacle, and means on the commodity receptacle which are adapted to be engaged by the means on the arm to enable the arm to rotate it.

13. In a vending machine, a commodity receptacle adapted to rotate, a pivoted arm for rotating the commodity receptacle, the center of rotation of the commodity receptacle being at a distance laterally from the pivot on which the arm is mounted, the arm being disposed substantially at right-angles to the axis of the commodity receptacle with its terminal adapted to describe an arc beyond the axis of the commodity receptacle, and a stud on the commodity receptacle, the arm having a slot and a recess therein, there being a tapered surface on the arm which extends from one side at one of the ends of the slot to the opposite side of the arm near the

lateral recess, the slot on the arm being adapted for engaging with the stud for operating the commodity receptacle when the arm is actuated, the stud being adapted for riding up the tapered surface to the lateral recess.

In testimony whereof I have signed my

name to this specification in the presence of two subscribing witnesses.

WILLIAM ASBURY.
